Des. 242,342
Patented Nov. 16, 1976

242,342

SUNGLASSES

Alexander Derkas, Phoenixville, Pa., assignor to American
Polarizers, Inc., Reading, Pa.

Filed Apr. 4, 1975, Ser. No. 565,047

Term of patent 14 years

Int. Cl. D2—03; D16—06
U.S. Cl. D16—70

FIG. 1.

FIG. 2.

FIG. 3.

FIG. 4.

FIG. 5.

FIG. 6.

FIG. 7.

FIG. 1 is a front perspective view of sunglasses showing my design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and

FIG. 7 is a bottom plan view thereof.

The broken lines near the ends of the temples indicate perforations.

I claim:

The ornamental design for sunglasses, as shown and described.
